UNITED STATES PATENT OFFICE.

GEORGE KELLY, OF LOS ANGELES, CALIFORNIA.

ADJUSTABLE STAGE CLAMP.

Application filed March 24, 1921. Serial No. 455,368.

To all whom it may concern:

Be it known that I, GEORGE KELLY, a citizen of the United States, residing at Los Angeles, in the county of Los Angeles and State of California, have invented new and useful Improvements in Adjustable Stage Clamps, of which the following is a specification.

It is the object of this invention to provide a support and adjustable clamping means adapted to be employed in connection with stage sets and the like in order to readily connect the various frames forming the stage setting and then support the same in upright position.

The invention will be readily understood from the following description of the accompanying drawings, in which

Figure 1 is a perspective view of one of the improved supporting clamping members showing the method of connecting the same to two adjacent frames of a stage setting.

Fig. 2 is a front elevation of the device showing the frame in vertical section.

Fig. 3 is a side elevation of the support of the device partly in vertical section and showing the method of attaching the same to the clamping member of the device.

Fig. 4 is a horizontal section on the line 30 4-4 of Fig. 2.

In the drawings I have shown usual frames forming part of a stage setting, said frames including side uprights 1 and suitable fabric surfaces 2 mounted upon the frames. The improved clamping and supporting mechanism is adapted to clamp together the side frames 1 of adjacent portions of the set, and to also support the frames as thus clamped together in upright position.

As an instance of this arrangement side plates 3 and 4 are arranged upon opposite outer surfaces of the frames 1 which are to be clamped together, and alined openings 5 and 6 are provided in the side plates and through the frames 1. A bracket arm 7 projects from one of the side plates shown as plate 4, and said bracket is provided with an elongated slot 8 adapted to receive a pivot bolt 9 having the cam 10 journaled thereon.

The cam preferably comprises a forked cam member having the operating handle 11 projecting from the same and adapted to receive a rod 12 between the forks of the cam and fixed upon pivot bolt 9. This rod extends through the openings 5 and 6 of the side plates and of the frames, and one sur-

face of the rod is notched along its length, as shown at 13, so that a dog 14 pivoted to side plate 3, may engage in any one of said notches for adjustably positioning the rod 60 with relation to side plate 3.

By disengaging dog 14 from rod 12, it will be noted that the frame carrying side plate 4 may be readily removed from the frame carrying side plate 3, by slipping rod 12 65 through the alined openings; and when it is desired to clamp the frame together, it is only necessary to aline the openings 5 and 6 of the two frames and insert rod 12 through said openings so that it may be engaged by 70 dog 14. By then swinging the cam upon its pivot through movement of its operating handle, the cam member will be moved along the length of slot 8 so as to adjust rod 12 with relation to side plate 4 and thereby 75 clamp the two frames together.

The support for the frames as thus connected includes a member pivoted to a bracket which may be secured to the floor, said member being detachably connected to 80 the connected frames at its opposite end as by a pivotally detachable connection.

For this purpose a stud 20 projects from one of the side plates shown as side plate 4, and said stud is provided with a laterally 85 projecting pin 21. The support includes an arm 22 having an opening 23 adapted to be received over stud 20. This opening is provided with a radial recess 24 adapted to receive the pin 21 in order that arm 22 may be 90 positioned upon stud 20 beneath locking pin 21. The surface of arm 22 surrounding opening 23 is arranged as a cam surface 25 so that when the arm is swung with relation to the stud in order to move pin 21 out of 95 alignment with recess 24 and therefore into position for locking the arm to the stud, the movement of the locking pin over the cam surface 25 will clamp the arm to side plate 4.

The arm 22 is connected to a suitable support 26 which, at its lower end, is provided with side plates 27 preferably extending beyond the end of the support. One of these side plates is preferably provided with a lateral projection 28 received between the 100 two side plates beyond the end of support 26 and having a concave surface 29 at its outer end forming a bearing. The side plates 27 project somewhat beyond the bearing surface 29 and are received against opposite 105 ends of a bearing 30 extending upwardly from a bracket 31 which is adapted to be se-

cured to the floor in any suitable manner as by nails or screws received through openings 32 provided in the bracket. A pivot pin 33 extends through the ends of side plates 27 and through the bearing 30 in order to provide a pivotal connection between the bracket and the support.

The construction, as thus described, provides extremely efficient means for clamping 10 together the frames of a stage set, or the like, and also affords a readily detachable support adapted to be connected to the frames so as to retain the same in upright position.

15. Various changes may be made without departing from the spirit of the invention as claimed.

What is claimed is:

1. In an adjustable stage clamp, the combination with frames having alined openings, 20 plates secured to the outer faces of the frames and having openings aligning with the openings in the frames, a dog carried by one of said plates, a bracket arm extending from 25 the other one of said plates and provided with an elongated slot, a bolt slidably mounted in the slot, a forked cam upon the bolt, an operating handle connected to the cam, and a notched rod mounted in the fork 30 of the cam upon the bolt and adapted to extend through the openings in the plate and frames and be engaged by the dog, so that when the handle is elevated and the cam pressed against the first plate the 35 notched rod will be engaged by the dog and then as the handle is lowered the cam will tighten and clamp the frames together.

2. In an adjustable stage clamp, a plate, 40 a stud projecting from the plate, a pin extending laterally from the stud, and an arm having an opening to receive the stud and a radial recess to receive the pin, there being a cam surface around the opening, so that when the arm is applied and rotated to 45 bring the pin out of alinement with the radial recess the parts will tighten.

3. The combination with frames, of means

for detachably adjustably clamping said frames, a support rotatably detachably connected at one end to said clamping means, 50 and a bracket having the other end of said support pivotally connected thereto, said bracket being detachably secured to a base.

4. The combination with frames having alined openings extending through the same, 55 of a clamping member extending through said openings and connected to one of said frames, means for moving said member relative to the other frame to clamp said frames, and a support connected to said frames.

5. The combination with frames having alined openings extending through the same, 60 of a clamping member extending through said openings, means for adjustably connecting said member to one of said frames, means for moving said member relative to the other frame to clamp said frames, and a support connected to said frames.

6. The combination with frames having alined openings extending through the same, 65 of a clamping member extending through said openings and connected to one of said frames, an operating cam pivoted to said clamping member and engaging the second frame to move said member so as to clamp 70 said frames, and a support connected to said frames.

7. The combination with a frame, of a support rotatably detachably connected at 75 one end to said frame, said connection including a cam surface adapted to draw said support to said frame when in attached position.

8. The combination with a frame, of a support, side plates projecting beyond said support, a lateral spacing member between said side plates beyond said support and forming a bearing, and a bracket having a bearing member received between said side plates and against said spacing member bearing.

In testimony whereof I have signed my name to this specification.

GEORGE KELLY.
